ALFRED RILEY HEATH, OF COVINGTON, INDIANA.

CAR-COUPING.

SPECIFICATION forming part of Letters Patent No. 634,341, dated October 3, 1899.

Application filed August 1, 1899, Serial No. 725,734. (No model.)

To all whom it may concern:

Be it known that I, ALFRED RILEY HEATH, of Covington, in the county of Fountain and State of Indiana, have invented new and useful Improvements in Car-Couplings, of which the following is a full, clear, and exact description.

This invention relates to an improved car-coupling of the hook-and-catch type; and it consists in the peculiar construction and combination of parts, as is hereinafter described, and indicated in the claims.

Reference is to be had to the accompanying drawings, forming a part of this specification, in which similar characters of reference indicate corresponding parts in all the figures.

Figure 1 is a sectional side view of the end portions of two car-bodies substantially on the line 1 1 in Fig. 2 and a side view of one improved coupling on each car in coupled condition. Fig. 2 is a plan view of the car-couplings shown in Fig. 1 and sectional portions of the two car-frames, taken substantially on the line 2 2 in Fig. 1; and Fig. 3 is an end elevation in part of a car-body and of the improvement thereon.

In the drawings which illustrate the construction and application of the improvement, A indicates a car-body, B an ordinary buffer-spring device held to project from the transverse timber A' of the car-frame for contact with a like buffer on another car, and C C a pair of depending carrier-beams whereon the buffer-spring device is maintained above the improved car-coupling that is supported on said beams so as to project its coupling-hook in advance of the cross-timber A'.

The improved car-coupling comprises an elongated body having suitable breadth and thickness for efficient service, the rear portion forming an integral draw-bar 4, from which extends at the forward end the integral hook member 5, a suitable shank 5^a intervening the hook member and draw-bar portion 4 of the car-coupling.

The hook 5 consists of a head whereon is formed the hook-lip a, which projects rearwardly from the main portion of the head and is separated sufficiently from the forward end of the shank 5^a to receive the cylindrical body of the rock-shaft 6, which will be fur-

ther described. Forwardly of the hook-lip a the head of the hook 5 curves downward and forward, having a convex front edge b on the 55 depending portion of the head, as clearly shown in Fig. 1.

A longitudinally-extended slot c is formed in the draw-bar portion 4 of the car-coupling body, having dimensions which will permit 60 the introduction within said slot of the coiled spring 7, which at its rear end receives the coniform nipple d, that is an integral projection from the rear wall of the slot c, the forward end of the coiled spring engaging in a 65 like manner with a nipple e', that is an integral formation on the fulcrum-box e, the use of which will presently appear.

The rock-shaft 6 is mainly cylindrical in the body and at each end is journaled in perforations formed to receive it in the carrier-beams C C, that extend a proper length longitudinally on the car body or frame thereof.

The front end wall of the slot c in the draw-bar portion 4 is rendered angular or notched, 75 as indicated at c' in Fig. 1, and upon the cylindrical body of the rock-shaft 6 where it passes through the slot c an integral V-shaped lug g is formed which fits neatly within the V-shaped notch c'. 80

The fulcrum-box e, previously mentioned, has its front side concaved to fit upon the cylindrical rear side of the rock-shaft body, and it will be seen that the constant pressure of the spring 7 will hold the lug g of the rock-shaft bedded in the notch c', whereby the car-coupling body complete is held to rock with the shaft 6.

On the upper side of the draw-bar portion 4 a longitudinal slot h is formed therein for 90 the reception of a laterally-bent arm i, which is a formation on the lower end of a lifting-rod 8.

The rod 8 extends upwardly at the front of the car-body and is of a length suited to the 95 character of the latter, as in case the car-body is low or of the gondola pattern, consisting merely of a platform and removable end and side boards thereon, which is a common construction. The lifting-rod 8 need only project a short distance above the transverse timber A' and may have a projection m in hook form projected laterally thereon. When the car-body is of the usual box pattern, (in-

dicated partially in the drawings,) the lifting-rod 8 is then upwardly extended to the roof of the car-body and terminates in a looped handle *n*. (Shown in Fig. 3.)

5 In either style of car construction the lifting-rod for the car-coupling is encircled by a staple *o*, driven into the front end of the car body or frame thereof, the position of the staple being a short distance above the hook-like projection *m*, which may pass up through said staple if the rod 8 is raised and at the same time held near the car end wall.

If at any time it is desired to temporarily support the rod 8 in elevated adjustment, 15 this may be readily effected by causing the hook member *m* to rest upon the transverse bar of the staple *o*, and when so lifted the hooked front end of the car-coupling will be rocked down in an obvious manner to avoid 20 coupled connection with another car-coupling.

A lateral member 9 is formed or secured on the upright lifting-rod 8 and projects therefrom to the side of the car for convenient 25 manipulation by an operator on the ground at the side of the car, and it will be seen that if this side rod or handle-bar is permitted to rest upon the cross-timber A' or other suitable projection on the end wall of the car the 30 drop of the lifting-rod 8 will be arrested at a point which will dispose the car-coupling body in or near a horizontal plane. It is to be understood, however, that a greater range of depression or elevation may be given to the hook 35 end of the car-coupling, if this is desired, by projecting the bar 9 from a point higher up on the lifting-rod 8.

The car-coupling is so positioned on the rock-shaft 6 that it will lie close to one carrier-beam C, and thus leave a space between the 40 coupling-body and the opposite carrier-beam C, which will expose a portion of the rock-shaft body for a hooked engagement therewith of another car-coupling of like construction.

45 On the body of the car-coupling, at or near the forward end of the draw-bar portion 4 thereof, a guide-flange 4^a is formed upon the same and projects laterally across the space 50 which intervenes between the coupling-body and the carrier-beam C said flange approaches. It will be seen that when a coupled engagement of two of the improved car-couplings is to be effected the convex front edge 55 on the hook member 5 will impinge upon the lower side of the guide-flange 4^a, and the latter will so depress and guide the hook member of the coupling as to enable the lip *a* to engage with the body of the rock-shaft said 60 lip passes beneath.

It should be explained that the weight of the lifting-rod 8 and the handle-bar 9 coact to maintain the car-coupling body level, and evidently when two of the improved car-couplings on approaching cars come together the rods 8 thereon will rise far enough to permit the hook portions 5 to hook upon respec-

tive rock-shaft 6 of the car-couplings, upon which they are guided by the lateral flanges 4^a, as before explained.

Near the forward end of the longitudinal slot *h* a draft-lug *p* is formed upon the body of the car-coupling and adapted to receive one end of a common coupling-link D, (shown partially in Fig. 1,) which provision enables 75 the coupled connection of the improved car-coupling with a common link-and-pin car-coupling, if this becomes necessary.

In operation of the improvement it will be seen that the spring 7 is adapted to absorb 80 all shocks due to suddenly-applied pulling strain, and by the novel construction of the draw-bar portion of the car-coupling said spring is carried thereon, dispensing with the ordinary means for the support of draft 85 cushion-springs. Furthermore, the car-coupling having its connection on the supporting rock-shaft 6 rendered elastic it is evident that two cars having the improved car-couplings may travel over curves in the railroad 90 and said couplings will yield laterally on the curves, thus avoiding any binding or improper friction where the hooks engage with the rock-shafts of the couplings.

At any time it is desired to detach two of 95 the improved car-couplings it is only necessary for the trainman to lift the rod 8 either from the car-body roof or from the side of the car, which will rock the hooks 5 of the engaged car-couplings down and release them 100 from the shafts 6, the enforced pressure of the lateral flanges 4^a upon adjacent coupling-bodies effecting such a result.

It will be evident that the peculiar construction of the car-coupling and means for 105 supporting the same on a car adapts the same for a great range of rocking adjustment, so that the car provided with the improved coupling may be coupled to another car that is either lower or higher and there will be no 110 cramping strain on either car-coupling so connected.

The practical nature of the improved car-coupling and its extreme simplicity, which renders it inexpensive to manufacture, are 115 obvious advantages pertaining to the improvement.

Having thus described my invention, I claim as new and desire to secure by Letters Patent—

1. In a car-coupling, the combination with a body having a hook member at one end, and a slotted draw-bar at the opposite end, of a supported rock-shaft at the forward end of the slot, a fulcrum-box engaging the rear side of the rock-shaft, and a buffer-spring in the slot having its ends respectively pressing upon the draw-bar and fulcrum-box.

2. In a car-coupling, the combination with a body having a hook member at one end, 130 and an integral longitudinally-slotted draw-bar at the opposite end, the front end of the draw-bar slot being angularly notched, of a supported rock-shaft having a lateral lug

which fits in the angular notch, a fulcrum-box concaved on one side which engages the rear side of the rock-shaft, and a coiled buffer-spring held in the draw-bar slot so as to press 5 upon the fulcrum-box.

3. In a car-coupling, the combination with a body having a hook member at one end, an integral longitudinally-slotted draw-bar at the opposite end, the front end of the draw-bar slot being angularly notched, and a guide-flange laterally projected from the draw-bar near the front end of the slot therein, of a supported rock-shaft having a lateral lug 10 that fits in the angular notch, a fulcrum-box concaved on one side which engages the rear side of the rock-shaft body, and a coiled 15 spring held in the draw-bar slot so as to press upon the fulcrum-box.

4. In a car-coupling of the character described, the combination with a coupling-body supported to rock near its longitudinal center along with a rock-shaft, and a buffer-spring carried in a slot of said body rearward 20 of the rock-shaft, and pressing a fulcrum-box thereon, the coupling-body having a hook on 25 its forward end, of a lifting-rod projecting upwardly from the coupling-body near the rock-shaft, a handle on the upper portion of the lifting-rod, a hook thereon adapted to engage a staple on the car-body, and a lateral 30 handle-bar on the lifting-rod.
